UNITED STATES PATENT OFFICE.

FRANK CHRISTENSON, OF DUNTON, LONG ISLAND, NEW YORK, ASSIGNEE TO JOHNS-MANVILLE INCORPORATED, A CORPORATION OF NEW YORK.

ROOFING.

Application filed September 29, 1921. Serial No. 504,040.

To all whom it may concern:

Be it known that I, FRANK CHRISTENSON, a citizen of the United States, residing at Dunton, Long Island, in the county of 5 Queens and State of New York, have invented certain new and useful Improvements in Roofings, of which the following is a specification.

This invention relates to roofing and has 10 for its object the provision of means whereby composition roofing may be laid in an economical manner and, when laid, will present an attractive appearance. The invention also seeks to provide roofing which may 15 be carried through the valleys of a roof without the employment of metallic structure. Other objects of the invention will appear incidentally in the course of the following description.

20 The invention is illustrated in the accompanying drawings, in which—

Figure 1 is a plan view of a portion of a roof having composition shingle strips laid thereon in accordance with my invention;

25 Fig. 2 is a section on the line 2—2 of Fig. 1;

Fig. 3 is a detail plan view of a portion of a roofing strip showing the manner of cutting the same.

30 My invention has special reference to roofing which is composed of asphalt and felt or similar flexible waterproof material and is furnished in strips rolled for transportation. Heretofore, these composition strips have had their edges parallel, and narrow notches with parallel walls have been formed at intervals along one edge so that, when the strips were laid in overlapped relation upon a building and transversely thereto, a similarity in appearance to ordinary shingle roofing was obtained. Such strips, however, have been objectionable for the reason that the corners of the strips would curl after the strips had been 35 in position for a short time and, moreover, the finished roof frequently had a flat and unattractive appearance. In a strong wind, the exposed portion of the shingle strip will turn up and will not return to normal position but will move, with the wind, knocking upon the roof timbers in a noisy manner. My improvement overcomes these 45 objections. In carrying out my invention, I provide sheet roofing in a strip 1 having 50 parallel longitudinal edges 2 and when the

strip is to be applied to a roof, I bisect the same along its center by forming cuts 3 therein disposed at right angles so as to intersect and thereby produce two strips having serrated edges. Waste of material is 55 thereby eliminated. At the ends of the strip, the diagonal cuts 3 are continued to the side edges of the strip, as shown at 4, and the points may be cut-off, as indicated at 5. The small portion cut from the ends 60 of the strip in this manner is placed at the corner of the roof with its edges alining with the edges of the roof, this portion being indicated by the numeral 6 in Fig. 1. The strips having the serrated edges are 65 then successively laid upon the roof structure on diagonal lines, as shown at 7, and the points or projections 8 formed by the serrations or intersecting diagonal cuts are caused to overlap the upper and side edges 70 of the portion 6 and the previously laid strips respectively, the overlapping arrangement being shown clearly at 9 in Fig. 2. The edges 4 of the strips will be caused 75 to coincide with the lower edge of the building or roof structure, as shown clearly in Fig. 1, and the edges of the projections 8 will successively register or aline with the edges of previously laid projections so that the completed roof will present lines extending 80 transversely and longitudinally of the roof free of notches and will thereby avoid curling and also present a very attractive appearance. Owing to the diagonal arrangement of the successive strips, the ends 85 thereof, more remote from the lower edge of the roof structure, may be carried directly through the valleys of the roof without the employment of any metallic foundation so that the cost of the finished roof will 90 be materially reduced and the time required for finishing the same minimized. It will be understood, of course, that each successive strip is nailed to the roof structure, as indicated at 10, and the nails or tacks 100 will preferably be so arranged that each tack will be covered by the projecting point of an overlapping strip. My improved roofing strips may be rolled for transportation and storage and may be readily cut at the 105 place of use. To facilitate the bisecting of the strips, lines may be marked thereon to guide the roofer in cutting the strips and precision in the work will be thereby insured.

My improved strip when in place exposes only one corner of a shingle and the strip cannot play up and down in the wind and work loose. When the roof is covered, it 5 will present lines running across as well as along the roof producing a unique and desirable appearance.

Having thus described the invention, what is claimed as new is:

- 10 The combination of a plurality of superposed roofing strips, the said strips being

provided each with one serrated edge and being laid diagonally on a roof whereby the serrated edge of each strip will overlap the straight edge portion of a previously laid 15 strip, and the serrated edges will define right angular projections having their sides extending in parallel lines transversely and longitudinally of the roof.

In testimony whereof I affix my signature.

FRANK CHRISTENSON.
